(57) CLAIM

The ornamental design for a shoe, as shown and described.

DESCRIPTION

FIG. 1 is a bottom rear perspective view of a shoe showing my new design;

FIG. 2 is a bottom view thereof; and,

FIG. 3 is a bottom front perspective view thereof.

The broken lines immediately adjacent to the internal perimeters of the shaded area represent the bounds of the claimed design and form no part thereof. The shading within the oval shapes represents a concave surface. The broken lines depicting the remainder of the shoe show features that form no part of the claimed design.
